CLAIM

The ornamental design for a bottle, as shown and described.

DESCRIPTION

FIG. 1 is a top perspective view of a design for a bottle having a first height;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof shown engaged with an unclaimed dropper bottle topper;

FIG. 9 is a top perspective view of the design for a bottle having a second height;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a top perspective view thereof shown engaged with an unclaimed spray bottle topper.

The broken lines in FIGS. 8 and 16 showing a dropper bottle topper illustrate environmental structures and form no part of the claimed design. The remaining broken lines portions of the bottle form no part of the claimed design.
